UNITED STATES PATENT OFFICE.

LINFORD S. STILES, OF BROOKLYN, NEW YORK.

METHOD AND MEANS FOR THE MANUFACTURE OF ILLUMINATING GAS.

Application filed June 10, 1920. Serial No. 387,838.

To all whom it may concern:

Be it known that I, LINFORD S. STILES, a citizen of the United States, and resident of Brooklyn, county of Kings, and State of New York, have invented an Improvement 5 in Methods and Means for the Manufacture of Illuminating Gas, of which the following is a specification.

The object of my invention is to provide 10 an improved method and means for producing illuminating gas, more particularly intended to improve the efficiency of the general character of apparatus heretofore in use by increasing the output capacity in gas, 15 reducing the time periods in which the apparatus is out of operation for cleaning and necessary repairs, and enabling the production of a satisfactory gas from inferior materials and especially from oil employed as 20 the medium of carburetting or enriching the hydrogen or blue gas.

My improvements are especially directed to that type of gas apparatus commonly known as water gas plants, in which coal 25 is raised to incandescence by air blast, steam is decomposed by the incandescent coal in the generator, the water gas so produced is carburetted by oil vaporized and mixed with it in a heated carburetter and the enriched 30 or illuminating gas so made is fixed by passage through a heated superheater and subsequently passed through a water seal to be delivered to the holder for consumption after undergoing purification. In com- 35 mercial practice, with a plant having a capacity of 3,000,000 cubic feet of gas per day, the set of apparatus can be run for about forty days (1000 hours) with the result that, with satisfactory oil having a paraffin base, 40 the checker brick filling of the carburetter will have become so heavily coated with de- 45 posits from the hydrocarbon in the oil and carbon from the generator, that the gas space through the staggered or checker brick filling will have been so greatly reduced and 50 clogging produced that the gas production drops off rapidly with corresponding inefficiency. The carburetter must then be shut down and cleaned. The superheater may be 55 run for about eighty days (2000 hours), as it fouls much more slowly than carburetter. Similarly, the generator may be run for about eighty days without repairs. From 60 this, it is seen that the carburetter requires

twice the attention for repairs which is necessary for the superheater and generator and consequently, when the plant is shut down for repairing the carburetter, the gas make of the entire set of apparatus is lost for the period required to cool off and re-checker the carburetter, which amounts to from seven to ten days; and hence in a cycle of forty-seven days, there are forty days in operation and at least seven days shut down, 55 making fifteen per cent of the time in which the costly plant is out of service. This is not only a direct loss on capital invested, but so reduces the production of gas per set of apparatus, that it necessitates additional 60 reserve installation in the plant, involving greater investment, and thereby increasing 65 the cost of the gas.

One of the special objects of my invention is to so modify the usual gas installation that not only is greater efficiency during operation insured, but the annual output in 70 gas per set of apparatus may be increased more than fifteen per cent with use of the same grade of fuel and oil. In carrying out this object of my invention, I provide 75 additional carburetter equipment which may be coupled into operative relation with the generator and superheater, in alternative relation with the carburetter commonly employed, by suitable controlling means, whereby continuous operations may be carried on for periods of eighty days instead of forty days and the obstructing difficulties from fouling may in a great measure 80 be reduced with resulting increase in gas production; and in those cases where the plant contains two "sets" of apparatus, the same advantages may be secured by the employment of one additional carburetter 85 adapted for use with the two "sets" alternately and alternately with the carburetters of each "set," thereby providing greater economy in cost of installation and space required.

In further considering the nature of my 90 improvements, I point out that it is not always possible to secure a satisfactory oil suitable as an enriching medium for the water gas (blue gas) which consists largely of hydrogen and carbon monoxide and which carburetted or enriched gas is "fixed" 95 by passing through the carburetter and superheater by which the gas is subjected to 100 105

high temperature fixation. Experience shows that the grade of oils available for gas production are deteriorating, in that instead of having a paraffin base they have an asphalt base and sometimes having objectionably large percentages of coke residue, in some cases as high as fifteen per cent. These oils are of lower specific gravity than what has heretofore been available in abundance, and the enforced use of them will ultimately and necessarily result by reason of the decreasing production of the higher specific gravity oils having the paraffin base. These low specific gravity oils having asphaltum and coke bases greatly increase the fouling of the checker brick in the carburetters and superheater, so that instead of permitting runs for 1000 hours (40 days) before cleaning of the carburetter is required, the cleaning will have to be done more frequently and therefore there will be a still further benefit to be derived by use of the additional or auxiliary carburetter, but its use will be mandatory if the plant is to be profitable to any extent, especially in cases where fixed maximum charges to the consumers are required under "Public service" control and oil for carburetting should increase in price. But while the auxiliary carburetter assists in the possible keeping down of the costs of production by increasing the efficiency of the plant, the tendency to foul the checker brick to a greater extent presents a new objectionable condition and this must be overcome to maintain a profitable operation of the gas plant, and to overcome this difficulty is another of the special objects of my invention.

In carrying out this latter object of my invention, I provide each set of apparatus with an auxiliary generator which is operated simultaneously with the main generator and in parallel therewith, whereby the gas products of both generators are supplied to the same carburetter at the same time and whereby they commingle and are subject to the same subsequent treatment in the carburetter and superheater; but in the production of the water gas in the two generators, there is a difference in procedure in the following respects: The main generator may be of the usual type and employed to produce water gas (blue gas) only; and it may be blown in one direction and, if desired, have the blue gas generated under reversed action, as by supplying the steam alternately above and below the incandescent bed of coal, coke or other fuel employed, valves being provided in the gas flues for insuring proper delivery of the gas to the carburetter under the reversed operation. The auxiliary generator differs from the main generator in operating only in one direction both for air blast and steam supply, and further in being supplied above the coal

bed with the enriching oil; and whereby, should the oil have an asphalt base or contain much coke residue, these objectionable ingredients will be largely burned up in the generator so that a very small proportion of them pass through with the more volatile hydrocarbons into the carburetter; and further, as there are no valves required as in the reversing operations of the main generator, the hydrocarbon products form the vaporized oil passing from the generator will not be objectionable, as would be the case if there were frequently operated valves through which they must pass and which would become gummed up or rendered inoperative. In this manner, not only is the auxiliary generator utilized to increase the gas output by keeping the generator capacity going twice as long during periods of peak load occurring in the several winter months of the year, and in compensating for the deficiency in gas production in cases where less oil is necessarily employed, but it provides an efficient means of handling low (Baumé) gravity oils having objectionable bases of asphalt and coke and preventing what would otherwise be an excessive fouling of the carburetters and superheaters.

With the above and other objects in view, the nature of which will be more fully understood from the description hereinafter, my invention consists in the method and means relating to the manufacture of illuminating gas as hereinafter more fully described and defined in the claims.

Referring to the drawings: Fig. 1 is a plan view of a two set gas plant embodying my invention; Fig. 2 is a sectional view taken on a vertical plane at the dotted line $x-x$ of Fig. 1; Fig. 3 is a horizontal sectional view along the flues from the generator to the plurality of carburetters showing a suitable valve for controlling the pipes in connection with the carburetters; and Fig. 4 is an elevation of a two set gas plant of a somewhat different lay-out than that shown in Figs. 1 and 2, but also embodying my invention and showing the generators partly in section.

More particularly referring to Figs. 1 and 2, there are shown two sets of gas apparatus associated with an auxiliary carburetter 3* and in considering my invention as applicable to a single set, this auxiliary carburetter may be taken as a part of such a single set equipment.

2 are the main gas generators, 3 the carburetters, 4 the superheaters and 5 the water seal boxes of each of the two sets of gas apparatus and these are associated with the auxiliary carburetter 3* and the necessary flues and control means for properly directing the flow of the gases as hereinafter more fully explained. The generators, carburetters, superheaters and water seal boxes are arranged in the order named, the water seal boxes being located between the generators and carburetters, and the superheaters being located between the carburetters and the water seal boxes.

retters, and superheaters may be of any usual construction, such as metal shells; firebrick lined, and in case of the two latter, provided with checker brick work. Such details need 5 not be described in detail, as I do not restrict myself in this respect. The main gas generator is preferably provided with blast pipe 6 at bottom, steam pipes 12 both at top and bottom for reversing operation when 10 generating water or "blue" gas, and gas flues 7 and 8 opening respectively from above and below the fuel bed chamber and each provided with control valves 11 of any suitable character. These flues 7 and 8 15 deliver beyond the valves into a common flue 9 which leads to the upper ends of the carburetters 3 and 3^a. These valves 11 are, respectively, alternately opened and closed, so that when steam is admitted by the 20 lower steam supply pipe 12 below the incandescent fuel bed, the valve in flue 7 is opened and valve in flue 8 closed, so that gas is generated and flows upward through the generator. Reversely, when steam is admitted 25 by the upper steam supply pipe 12 above the incandescent fuel bed, valve 11 in flue 7 is closed and valve 11 in flue 8 is opened, so that the gas flows down through the generator. The blast, when supplied, 30 always enters the generator at the bottom below the fuel bed, and as is well understood, the air blast and steam are supplied alternately.

The flue 9 from generator 2 leads to 35 carburetter 3 by flue 10^b and to carburetter 3^a by flue 10^a, and the gases are supplied to these carburetters alternately according to the adjustment of the valve devices 19 which will be later described. The lower 40 ends of the carburetters 3 and 3^a are connected with the bottom portion of the superheater 4 by flues 4^b and 4^a, respectively, which are also controlled by suitable valve devices 19^a, to co-operate with the control of 45 the valve devices 19, whereby either carburetter 3 or 3^a may be coupled in operative relation with the superheater.

The carburetters 3 and 3^a are provided 50 with air blast pipes 20 at their upper ends to aid in heating them by burning the gas from the generator when blowing up. Similarly, the superheater 4 is provided at the bottom with air blast pipe 21 to assist in heating it up under the same conditions. 55 The carburetters are also provided at top with oil supply nozzles 13 and the superheater with escape valve 14 for temporarily venting the waste gases when heating up preparatory to a run of illuminating gas. The illuminating gas from the superheater passes through the seal box 5 and is delivered by conduit 15 to a holder.

In addition to the ordinary set of gas apparatus supplemented by the auxiliary carburetter 3^a, I also provide an additional

or auxiliary generator 16 which is connected at its upper part by a flue 10 which communicates not only with the flue 9 of the main generator 2 but also with flues 10^a and 10^b, leading to the carburetters. This auxiliary generator 16 is supplied with blast pipe 17 and also with a steam supply pipe 19^a at the bottom, so that in its operation, both in blowing and generating water gas, the air and steam employed is fed to the generator below the fuel bed and the gases rise upwardly through the fuel. The steam supply is not reversed as in the main generator. In addition to the capacity for generating "blue" gas, the generator is provided with an oil supply nozzle 18 for supplying the oil to the top of the generator and preferably upon the incandescent fuel therein, whereby the more volatile portions of the oil will be vaporized and mixed with the "blue" gas to constitute a rich carburetted water gas which is conducted off by flue 10 and mixed with the "blue" gas from generator 2 preliminary to the mixture passing into the carburetters 3 and 3^a. In this manner, the coke residue or asphalt base of the oil is burned up in the generator 16 and prevented from forming excessive deposits on the checker brick of the carburetters with the resulting objectionable and rapid clogging of the same. While the generator 2 is provided with the reversing valves 11, there are no similar valves arranged in the flue 10 between the auxiliary generator 16 and the carburetters which could be clogged by the heavy hydrocarbon vapors passing from the generator 16 and arising from the oil delivered therein. It is important that this flue 10 from the generator 16 shall be unobstructed to provide a free passage at all 105 times into the carburetter in use, as any valves which are required to be shifted frequently during the run of the plant would soon become clogged and inoperative where the hydrocarbon enriching material was 110 vaporized in the generator and required to pass through them. In practice, the reversing valves 11 and generator 2 are required to be operated at intervals of a few minutes 115 and consequently in a generator in which the oil is vaporized, it is important that valves of this character shall be eliminated, and this is accomplished by employing an auxiliary generator in which the hydrocarbon is admitted with every run of gas. If the oil 120 were admitted to the top of generator 2 when the steam is admitted to the bottom of the bed of coal, the generation of the hydrocarbon vapors would be intermittent with the generation of "blue" gas, and, therefore, objectionable in this respect. But aside from this, the heavy hydrocarbon vapors would clog the valve 11 in the upper flue 7 and in a short time make it difficult 125 or impossible to operate the generator 2 130

properly without frequent cleaning of the valves and loss of capacity of the plant thereby.

This combination of an auxiliary generator with oil supply and the main generator without oil supply and preferably with reversing capacity for the steam is an important feature of my invention, where low grade oils having objectionable bases are necessarily employed either because of lack of production of high grade oils having a paraffin base or because of the necessity of economy in case of available oils. By insuring the separation and burning up of the asphalt or coke base of the oil, I am enabled, in this manner, to maintain the run of a thousand hours or more with the use of a carburetter before requiring cleaning repairs, and furthermore, I am enabled to maintain the total output of gas from the plant, notwithstanding the decreased gas value of the oil of inferior quality which may thus be employed, whether voluntarily or by necessity. Should the richness of the water gas in hydrocarbons be insufficient to meet the requirements under which the plant is required to operate, some additional better grade oil may be supplied to the carburetters by the nozzles 13 in the manner heretofore customary; and in fact, in those cases where the high grade oils become available, the entire oil supply may be provided by the nozzles 13, if so desired, and the generator 16 only employed for furnishing additional "blue" gas at those times of the year when the peak load is especially heavy.

My improved apparatus may thus be operated as a single set but in large plants there are two or more sets required and I have, therefore, indicated in the drawings, Figs. 1 and 4, the arrangement of a two set plant, and the economy in connection with a two set plant resides in employing a single auxiliary carburetter 3^a as a common unit to each of the two sets. Thus, in Fig. 1, it will be understood that the generators of the left-hand set may be operated in connection with the carburetter 3 or the carburetter 3^a, as may be required, and similarly, the generator of the right-hand set may be operated in connection with the other carburetter 3 of its own set or the auxiliary carburetter 3^a, as required. The combined operation of the two sets is, however, so controlled as to time of cleaning the carburetters, that the auxiliary carburetter 3^a may be cleaned twice as often as the carburetters 3 and superheaters 4, if so desired, but it is also manifest that the runs may be made through the carburetters 3 from each set of generators for twice the period that they would be run from the respective sets of generators through the auxiliary carburetter 3^a, so that the ultimate duty of each of the carburetters 3 and the carburetter 3^a may be substantial-

ly equal. This proportioning as to the duration of use of the carburetters 3 and 3^a in connection with the respective sets of generators is a matter which may be varied to suit the engineering requirements.

I have heretofore referred to the valve devices 19 which are to control the flow of gas from the generators to the carburetters 3 or 3^a, as the case may be, and from these carburetters to the superheater 4, and I will now refer to the preferred construction which is more fully illustrated in Fig. 3. By reference to Fig. 3, it will be seen that the flues 10, 10^a and 10^b, form a Y and at the branching point there are flange structures 20 between which a valve plate 19 is inserted and which may be clamped in adjusted positions by the bolts 21. This plate is provided with an aperture 19^b which has a diameter corresponding to the interior of the lined flues, so as to provide a clear through passage from flue 10 to flue 10^b, as shown, or from flue 10 to flue 10^a, as may be required. The plate, therefore, presents a blank to shut off one of the flues 10^a or 10^b, while leaving the other open into the flue 10. When this shifting is to be performed, the bolts 21 are removed and the plate 19 shifted, the bolt inserted and the parts definitely clamped in the new adjustment. In a valve device of this character, there is no possibility of clogging and as it is shifted at long intervals apart, there is no special objection at the time required to perform the shifting operation. It is far more important that there shall be no clogging and no difficulty arise when it is necessary to make the shifts. The valve devices 19^a in the flues 4^a and 4^b providing communication from the carburetters 3 and 3^a to the superheater 4 are made in a similar manner to those already described in connection with the flues 10, 10^a and 10^b, but I wish it to be understood that I do not restrict myself as to the construction of these valves, as they may be made in any suitable manner found satisfactory.

In the foregoing description of a gas plant embodying my improvements, I have assumed that all of the generators, carburetters and superheaters were arranged upon the same floor, as is sometimes customary, but in other cases where insufficient space is available, it is customary to build the superheaters and carburetters at a higher elevation than the generators and in which cases the superheaters may be built directly upon the main generators. My invention, therefore, may be modified in the general lay-out to correspond substantially to what is shown in Fig. 4. In this case, 2 represents the main gas generators, 4 the superheaters, 3 and 3^a the carburetters, and 16 the auxiliary gas generator, all as provided for in the construction illustrated in Fig. 1. In this illustration I have indicated the valve devices 19

and 19^a, as independent means in each flue; and whether they be in the form of shifting valves of ordinary construction or made by ring and blank division plates for simplicity 5 and lack of parts to collect carbon deposits, it is immaterial to my invention and, therefore, these parts 19 and 19^a may be taken as diagrammatic illustrations of means which, by proper manipulation, are adapted to control 10 the flue passages. From reference to Fig. 4, it will be seen that all of the generators 2 and 16 are located on the lower floor of the building while all of the superheaters and carburetters are located on the upper 15 floor of the building, and in this manner, it is manifest that less floor space for the building will be required than when all of the elements making up the plant are arranged upon the same floor.

20 I have described my improved method and means in that particularity which I deem to be the best exposition of my invention, and that which I prefer in commercial practice, but I do not restrict or confine myself to the 25 minor or secondary details, as such are susceptible of modification, which may be resorted to as matters of mechanical skill and without a departure from the spirit of the invention.

30 Having now described my invention, what I claim as new and desire to secure by Letters Patent, is:—

1. In a gas apparatus, a water gas generator having blast and steam pipes, combined 35 with a superheater, two carburetters through which the water gas from the generator flows to the superheater, gas flues connecting the generator with the inlets of the two carburetters and having means for controlling the 40 communication of the generator with the two carburetters, whereby they may be alternately put into and out of operative communication with the generator, gas passages from the outlets of the carburetters connecting 45 with inlet of the superheater, and separate means for supplying oil to the respective carburetters whereby the vapors arising therefrom are commingled directly with the water gas passing through the carburetters, 50 the construction of the carburetters being such that the water gas in carburetted condition is delivered into and through the superheater for being "fixed" therein.

2. The invention according to claim 1, 55 wherein further, the means for controlling the communication with the carburetters are formed of adjustable plates, each in a plurality of flues and providing annular union parts for open communication in a portion of the flues and blank union parts for closed connections in the remaining flues.

3. The invention according to claim 1, further characterized by the water gas generator having means for supplying steam both to 60 its upper and lower portions and flues with

valves therein for reversing the gas flow through the generator and delivering the water gas to the carburetters, and an auxiliary water and oil gas generator having means to supply steam at its bottom and 70 means to supply oil at its top to carburet the water gas produced, and a gas passage leading from the auxiliary generator for supplying carburetted gas to the carburetters along with the water gas from the other 75 generator.

4. In a gas apparatus, a water gas generator having steam supply pipes both at the upper and lower portions and also having flues with valves therein for reversing the 80 gas flow through the generator, combined with a superheater, two carburetters through which the water gas from the generator flows to the superheater, gas flues connecting the generator with the inlets of the two carburetters and having means for controlling the communication of the generator with the two carburetters whereby they may be alternately put into and out of operative communication with the generator, an auxiliary 85 water and oil gas generator having means to supply steam at its bottom and oil at its top to carburet the water gas produced, a gas passage leading from the auxiliary generator for supplying carburetted gas to the 90 carburetters along with the water gas from the other generator, said gas passage from the auxiliary generator formed of a constantly open passage leading from the same 95 end of the generator into which the oil supplying means is connected, gas passages from the outlets of the carburetters connecting with the superheater, and separate means for supplying oil to the respective carburetters whereby the vapors arising therefrom are 100 commingled directly with the water gas passing through the carburetters, the construction of the carburetters being such that the water gas in carburetted condition is delivered into and through the superheater for 105 being "fixed" therein.

5. The invention according to claim 1, characterized by having an auxiliary water and oil gas generator operatively connected in parallel relation with the main generator 110 and provided with a gas outlet at its upper part for communication with the carburetters, means to supply air blast and steam to its lower part, and means to supply oil to its upper part.

6. A gas generating plant, comprising two water gas sets each composed of a generator, a carburetter, a superheater and a water seal and connecting flues for passing the water gas from the generator successively through the carburetter, superheater and water seal, and an additional carburetter and connecting flues for putting said carburetter into communication with the generator and superheater of either set at any one 125 130

time, and means for causing the circulation of water gas from each of the generators through the carburetter of its own set or through the additional carburetter whereby the latter may be employed with the generators of the two sets alternately.

7. The invention according to claim 6, further provided with two auxiliary water and oil gas generators, one for each set, said generators each provided with means for supplying steam at the bottom and oil at the top and further having flues for delivering the carburetted water gas produced in said auxiliary generators to the carburetter of the respective set or to the additional carburetter according to the adjusted connections thereof with the generator.

8. In a gas apparatus, a main generator for producing uncarburetted water gas, a carburetter, a superheater, a water seal, and communicating flues whereby the water gas may pass from the generator successively through the carburetter, superheater and water seal, combined with an auxiliary water and oil gas generator provided with steam supply at the bottom and oil supply at the top to produce a rich carburetted water gas, and having a flue for direct delivery of the gas into the carburetter where it is thoroughly commingled with the water gas from the main generator prior to fixation.

9. The herein described method of generating an illuminating water gas with use of an oil having an asphalt base which consists in generating uncarburetted water gas in one generator having an incandescent bed of fuel, generating water gas in another generator also having an incandescent bed of fuel and immediately carburetting the water gas by supplying to said generator above the fuel bed therein a heavy oil having an asphalt base whereby the more volatile hydrocarbons are vaporized and commingled with the water gas passing from the generator and the objectionable asphalt and other non-volatile bases of the oil are consumed by combustion within the generator, mixing the carburetted water gas with the uncarburetted water gas from the respective generators and their incandescent beds of fuel and supplying the mixed gases to the action of a highly heated carburetter to reduce the mixture to a homogeneous carburetted condition, and thereafter fixing the carburetted water gas so provided by passing it through a highly heated fixing chamber.

10. The herein described method of generating an illuminating water gas with use

of an oil having an asphalt base which consists in generating uncarburetted water gas in one generator having an incandescent bed of fuel by blowing the generator in one direction only and in supplying steam alternately to the upper and lower portions of the generator, generating water gas in another generator also having an incandescent bed of fuel by blowing it always in one direction and supplying the steam below the fuel bed to generate water gas and immediately carburetting the water gas by supplying to said generator above the fuel bed therein a heavy oil having an asphalt base whereby the more volatile hydrocarbons are vaporized and commingled with the water gas passing from the generator and the objectionable asphalt and other non-volatile bases of the oil are consumed by combustion within the generator, mixing the carburetted water gas with the uncarburetted water gas from the respective generators and their incandescent beds of fuel and supplying the mixed gases to the action of a highly heated carburetter to reduce the mixture to a homogeneous carburetted condition, and thereafter fixing the carburetted water gas so provided by passing it through a highly heated fixing chamber.

11. The invention according to claim 10 further characterized by supplying additional oil of a lighter and more volatile character to the carburetter to further enrich the gas mixture before passing out of the carburetter to the fixing chamber.

12. The herein described method for maintaining a gas apparatus continuously in operation which consists in generating a water gas in suitable generating apparatus and supplying it to two highly heated carburetters wherein it is fully enriched with oil and made homogeneous as to quality, thereafter supplying the hydrocarbon gases from the carburetters to a highly heated fixing chamber wherein the carburetted gas is fixed prior to storage, controlling the flow of the water gas from the generator apparatus and delivering it to the two carburetters alternately and similarly controlling its delivery whereby the carburetted water gas is supplied alternately from said carburetters to the superheater, and during the period that the gases are flowing from one carburetter to the superheater, cleansing the interior of the other carburetter and vice versa.

In testimony of which invention, I hereunto set my hand.

LINFORD S. STILES.
